UNITED STATES PATENT OFFICE.

ADOLPHUS S. DENNIS, OF CLEVELAND, OHIO, ASSIGNOR, BY MESNE
ASSIGNMENTS, TO THE CALULUS COMPANY.

COMPUTING-MACHINE.

No. 842,138.

Specification of Letters Patent.

Patented Jan. 22, 1907.

Application filed September 25, 1905. Renewed December 22, 1906. Serial No. 349,161.

To all whom it may concern:

Be it known that I, ADOLPHUS S. DENNIS, a citizen of the United States, residing at Cleveland, in the county of Cuyahoga and 5 State of Ohio, have invented certain new and useful Improvements in Computing-Machines; and I do declare that the following is a full, clear, and exact description of the invention, which will enable others skilled in 10 the art to which it appertains to make and use the same.

My invention relates to computing-machines, and is an improvement on a machine for which an application was filed by me December 19, 1904, Serial No. 237,439; and the improvement consists in the construction and combination of parts substantially as shown and described, and more particularly pointed out in the claims.

20 My aim is to produce a simple computing device of small size with a wide range of work and wherein the manipulation is speedy and definite and especially adaptable for quick results and whereby any given amount 25 or sum may be computed and the answer read at a glance. As shown, the machine is adapted for computing sums in multiplication or division, but is not necessarily limited to this use.

30 In the accompanying drawings, Figure 1 is a plan or face view of the machine broken away at its center, and Fig. 2 is a face view of the index-plate used in said machine. Fig. 3 is a cross-section of the index-plate above 35 described. Fig. 4 is a cross-section of different portions of the machine looking in from line $x-x$, Fig. 5. Fig. 5 is a longitudinal section on line $y-y$, Fig. 4, and with the central portion of the device broken away. Figs. 6, 40 7, and 8 are separate face views of the computation-sheets attached to the first, second, and third set of rollers, respectively.

One of the main and most important features of my improved machine is embodied 45 in the plural arrangement of independently-rotatable sets of rollers A, B, and C, each set of which is adapted to operate singly for the computation of arithmetic problems or in combination and jointly when used with an 50 index-plate D. To these ends I utilize separate sheets of flexible strips, the opposite ends of which are fastened to the oppositely-ar-

ranged roller in each set, and which sheet is adapted to wind upon one roller as it is unwound from the other roller, a joint action 55 and the rotation of both rollers in the same direction being provided for by gearing, as hereinafter more fully described. Each set of rollers A, B, and C is thus equipped with sheets a , b , and c , respectively, and each 60 sheet is provided upon its exposed face with columns of figures in parallel lines and with a designating-figure at the top of each column, which represents either the multiplicand or divisor of each item in its respective column. 65 In the present instance sheet a has a series of parallel columns numbered from "1" to "100," inclusive, and the items in each column represent either the product or the dividend as related to the designating-figure at 70 the top, and said items are consecutively arranged to align with certain figures upon index-plate D, numbered from "1" to "100," inclusive, to represent the multiplier or quotient of an example in either multiplication 75 or division, as the case may be.

Index-plate D is slotted at d in the several places directly over the different sets of rollers to expose single columns of figures upon the respective sheets, and as said sets of rollers 80 are independently rotatable any desired column may be brought to view. Thus, for example, if "2" was the known multiplicand sheet a upon rollers A would be operated to bring the column designated by "2" into 85 view, as seen in Fig. 1, and then choosing any one of the figures upon the index-plate—say "100"—it will be seen at a glance that the product is "200," which latter figure is directly opposite upon sheet a . 90

Sheets b and c are exactly similar in arrangement and operate the same as sheet a above described, except that different figures are used. Thus sheet a has its columns of figures arranged and designated from "1" to 95 "100," inclusive, whereas sheet b is numbered and arranged from "101" to "200," inclusive, and sheet c from "201" to "300," inclusive. Thus the three sheets taken together have three hundred columns of figures, each column of which is designated at its head by its proper number. Any one of the three sheets may be operated to bring any particular column into view to read the 100

answer in a problem of multiplication or division within the range of the figures on the selected column and the index-plate.

- In a problem of multiplication the index-plate column of figures represents a multiplier, the heading at the top of any column on either sheet represents the multiplicand, and any item of a column of figures upon the said sheet represents the product—that is, 5 each item of the sheet opposite the item upon the index-plate being the product thereof and of the multiplicand at the top of the exposed column of the sheet. To find the quotient in a problem of division, the number at 10 the head of any column upon either sheet is used as the divisor any number in a column on said sheet as the dividend, and the number on the index-plate opposite the one selected on said sheet is the quotient. Thus 15 20 the true and correct answer for any problem in multiplication or division may be readily ascertained by bringing any one of the columns of figures on the sheet attached to the rollers into view opposite the column of figures on the index-plate, and the range of multiplication and division is only limited by the 25 number of columns or number of figures in each column. For practical reasons there must be a limit; otherwise the device would 30 be too cumbersome to handle because of its size. I have therefore conceived the idea of a plurality of sets of rollers and separate sheets arranged side by side, said rollers being independently rotatable and each additional set of rollers and sheets therefor having columns of figures of higher denomination than the one preceding. The advantage of this construction arises from the fact that by a joint use of the several sets of rollers and 35 40 45 50 55 60 65 70 75 80 85 90 95 100 105 110 115 120 125 130 separate sheets a very wide range of arithmetical problems can be easily and quickly computed. To illustrate this point, let us take an example in multiplication wherein the multiplicand runs into the thousands and, say, is of four figures, as "2101." The highest multiplicand is "300" and is on sheet *e*, and therefore no single roll or sheet has the product thereon; but by using rollers A and B and sheets *a* and *b* said multiplicand and the product of any multiplier upon the index-plate can be obtained thus: Roller A would be operated to bring column "2" on sheet *a* into view, as seen in Fig. 1, and then rollers B would be rotated to expose column "101." Then reading from left to right the heading numbers of sheets *a* and *b* read "2101" as the multiplicand. Now taking any item upon the index-plate as the multiplier—say "3"—the product is seen opposite said multiplier, a portion upon each sheet, and must be read from left to right, the total appearing as "6" on sheet *a* and "303" on sheet *b* and reading "6303," as the correct product. If "10" were used for the multiplier, the reading 55 would be somewhat different, as the correct

product is obtained by adding the products upon each sheet opposite the multiplier "10" together, thus:

$$\begin{array}{r}
 20 \\
 1010 \\
 \hline
 21010
 \end{array}
 \quad 70$$

In this case the column "2," roll A, does not stand alone as a units-column, but becomes 75 the thousands-column, and the units, tens, and hundreds column is on the roll to the right. Taking a still larger number as the multiplicand to bring the rollers C and sheet *c* into use—say "2,101,250"—and using "100" 80 as the multiplier, the product is obtained by rotating rollers A to bring column "2" into view, then rotating rollers B to expose column "101," and finally operating rollers C to expose column "250." Column "2," roll A, 85 becomes the millions-column and six imaginary ciphers are added to the item on sheet *a* opposite the multiplier on the index-plate, the column on sheet *b*, rollers B, represented by "101" becomes the thousands, tens-of-thousands, and hundred-of-thousands column and three imaginary ciphers are added to the item on sheet *b* opposite the multiplier selected, and finally the column on sheet *c*, represented by "250," becomes the units, 90 tens, and hundreds column. The three items on the respective sheets opposite the multiplier selected—in this example "200"—are added together thus:

$$\begin{array}{r}
 200\,000\,000 \\
 10\,100\,000 \\
 25\,000 \\
 \hline
 210,125,000
 \end{array}
 \quad 90$$

This is the correct product of the example given, and any product can be thus obtained having any given multiplicand and a multiplier within the number of the columns on the several sheets and the items on the index-plate.

Referring now more particularly to the details of construction, it will be seen that the device comprises a rectangular box or casing *E* open at its top, excepting for a glass cover *F*, which rests over and upon index-plate *D*. Caps or pieces *e* inclose the casing at its ends and confine and hold the various parts in place. Rollers A, B, and C have each trunnions or a shaft *g* with bearings in inner walls or plates *G*, and each roller has a pinion *H* at one end of its shaft or trunnion. Each set of rollers and its pinions are provided with a gear *I*, which meshes with each pair of pinions *II*, and said gear is mounted on a short shaft *J*, projecting through plate *G* and end cap *e*, and a thumb-nut or milled head *K* for said shaft at the outside of said casing is used to rotate each gear *I* and its respective 125 130

drive-pinions and rollers independently of the other sets.

Each roller of the respective sets of rollers is provided with a disk or washer K', mounted on the end thereof and between and flush with pinion H on shaft 3, and each washer fits within an opening L in plate M, forming a division-wall between the rollers and the gearing at one end of the casing, and said plate further serves to guide the strips a, b, and c in true alinement upon their respective rollers and also out of engagement or entanglement with the gears. Division-wall M also acts as inner journal for gear I.

The utility and advantage of having a series of similar index-columns for the several sheets is clearly shown by the following example: Thus to multiply "2,101,250" by "83" the first step is to set up heading number "2" on the first sheet a, then "101" on the second sheet b, then "250" on the third sheet c, so that the combined figures at the top of the sheets will read from left to right as "2,101,250." The multiplier "83" is seen in three places in line across the index-plate, one for each sheet, and the answer is found by beginning at the right and may be written down on paper step by step, if desired, and in that event the first item of the answer to be marked down would be "750," forming part of the number "20,750," which is found under the column headed "250," directly opposite the index-figure "83" at the side of said column. Then the "20," which is the thousands of said number "20,750" on sheet c, is carried over to the column headed "101" and added to the figure "8,383" shown opposite index-figure "83" at the side of said column "101," thereby making the sum of "8,403,750." Then the "8," representing millions in this column, would be added to the number "166" in the millions-column on sheet a, and which number "166" is readily found as marked by index-figure "83," opposite said column on sheet a. The correct product, "174,403,750," is thus obtained without mistake or confusion, as each part of the answer is identified by the same index-figure at the several columns. Another example, showing the desirability of having index-figures in close proximity to each column, is to be found in a problem combining both multiplication and division. Thus, supposing the number "9,393" is to be divided by "101" and the quotient thereof to be multiplied by "250," the first step is to find "9,393" on sheet b under the column headed "101," and then the quotient is at once seen by referring to the index-column opposite said number "9,393" and which in this case is number "93." Now to multiply this quotient "93" by "250" the next reference is

to the index-column for sheet c, and when the column headed "250" is shown up the number in said column opposite the number 65 "93" of the index-column will at once disclose the correct product, which in this example is "23,250."

What I claim is—

1. In a computing-machine, a casing having visual openings, two or more pairs of rollers in axial alinement, the rollers of each pair being superposed one above the other, whereby the top rollers may be brought close together, and each pair being independently operative, in combination with an index-strip fixed between each pair of rollers and having in each instance the same series of index-numbers thereupon, the same numbers in each series being in horizontal alinement, 80 and a separate sheet for each pair of rollers having columns of figures in parallel alinement adapted to show through said visual openings, said openings being adjacent to and parallel with said index-strips, and the corresponding numbers on the sheets and index-strips being also in horizontal alinement.

2. In a computing-machine, a casing having visual openings, two or more pairs of rollers in axial alinement, the rollers of each pair being superposed one above the other, whereby the top rollers may be brought close together, and each pair being independently operative, in combination with an index-strip fixed between each pair of rollers and 90 having in each instance the same series of index-numbers, running from 1 to 100 thereupon, the same numbers in each series being in horizontal alinement, and a separate sheet for each pair of rollers having columns of figures in parallel alinement adapted to show through said visual openings, said openings being adjacent to and parallel with said index-strips, and the corresponding numbers on the sheets and index-strips being also in horizontal alinement.

3. In a computing-machine of the kind described, a casing, a series of pairs of rollers, each pair carrying a sheet, a gear-wheel at one end of each roller, a driving-gear for each pair of gear-wheels, a division-wall separating the ends of the rollers proper from said gear-wheels and driving-gear and forming a guide for said sheets and also an inner journal for the driving-gear, and a washer upon the end of each roller fitting within an opening in said division-wall.

In testimony whereof I sign this specification in the presence of two witnesses.

ADOLPHUS S. DENNIS.
